ART OF REMOVING ASPHALT FROM
ASPHALT BASE OILS

David G. Brandt, Westfield, N. J., assignor to
Power Patents Company, Hillside, N. J., a cor-
poration of Maine

Application May 16, 1933, Serial No. 671,317

5 Claims. (Cl. 196—13)

This invention relates to a process and apparatus for removing asphalt or bituminous materials from asphaltic petroleum oils, and more particularly for the recovery of valuable oil constituents and the production of marketable asphalt.

The asphalt used for making roads and for various purposes in the arts, is derived either from natural sources or from selected asphaltic petroleum oils. The usual procedure for obtaining asphalt from petroleum oils containing the same, is to distill the oil down to a heavy residue and use the whole of the residue after blowing with air, or other treatment, for the production of road asphalt or other asphaltic products. Such processes however, have been very wasteful of valuable oil constituents, particularly paraffin hydrocarbons, which are suitable for the manufacture of lubricating oils.

20 The primary object of the present invention is the production of a high grade asphalt and the recovery of valuable oil constituents which have been heretofore waste.

A further object of the invention is the provision of a process for removing asphalt from petroleum oil residues such as are formed from the distillation of asphaltic petroleum oils (mixed base or asphalt base oils) or produced in the cracking of petroleum oils.

30 The process of the present invention includes a relatively simple and effective procedure for removing asphalt from asphalt-containing oils which includes the steps of forming a mixture of the oil to be treated with a low molecular weight hydrocarbon diluent at a superatmospheric pressure and at a temperature suitable for the precipitation of the asphalt, passing the mixture into a settling zone in which the asphalt is allowed to precipitate or settle out, and thereafter separating the hydrocarbon diluent from the oil separated from the asphalt.

The present invention also includes the use of a novel apparatus as well as other features, objects and advantages which will be apparent from the following detailed description taken in connection with the accompanying drawing in which:

The figure is a diagrammatic view partly in section of an apparatus adapted to carry out the steps and features of the improved process.

50 The oil from which the asphalt is to be removed and which may be mixed base or purely asphalt base oil, is withdrawn from a chamber 2 through a line 4. The chamber 2 may represent the lower portion of a cracking chamber, distilling cham-

ber, or other chamber from which the oil is withdrawn through the line 4 in a heated condition at a temperature for example of from 450° to 750° F. This oil containing a substantial proportion of asphalt is forced by means of a pump 6 and a line 8 through a heat exchange coil 10, mounted in the lower portion of a pressure still 12, wherein the heat of the oil passed through the coil 10 is used for vaporizing the low molecular weight hydrocarbon from the asphalt-free oil 10 produced in the process. The oil leaving the coil 10 is then conducted through a heat exchanger 14, a pipe 16, and then through a cooler 18 from which the oil passes at a temperature of from 50° to 130° F., through a pipe 20, in which is 15 mounted a recording flow meter 22, or measuring device, and a branch pipe 24, into a mechanical mixer 26. In the pipe 24 and mixer 26, the asphalt-bearing oil is intimately mixed with a predetermined quantity of a low molecular weight 20 hydrocarbon such as liquid propane, and the mixture is conducted by means of pipes 28 and 30 and a branch pipe 32 into the first of a series of pressure settling chambers 34, 36 and 38. The chambers 36 and 38 are connected with pipe 30 25 by means of valved branch pipes 40 and 42 respectively.

The diluted oil mixture containing from 10% to 75% liquid propane by volume, is conducted under pressure through the line 32 into one end 30 of the chamber 34 and allowed to completely fill the chamber, so that thereafter the diluted oil flows through the chamber in a quiet manner, thus permitting the asphalt to settle out. Under these conditions, experiments have shown that 35 because of the low viscosity and gravity of the oil blend, the asphalt settles in a manner comparable to the settling of sand from water. The oil mixture in the chamber 34 is completely freed 40 of asphalt and the clear asphalt-free oil blend is conducted from the chamber through an overflow line 44, into a valved discharge line 46 by which the oil is conducted to a pump 48 and forced through a connecting line 50, a heat exchanger 52 and heat exchanger 14 into the upper 45 mid-portion of pressure still 12. The asphalt-free oil blend passing through the heat exchangers 52 and 14 is heated to a substantial extent and then discharged on to a distributor tray 53 so that the oil mixture is rained or sprayed over 50 the coils 10 mounted in the lower part of pressure still 12. The heat derived from the heat exchangers 52 and 14 and the coil 10 is sufficient to vaporize substantially all of the propane contained in the oil blend.

The propane vapors are conducted from the still 12 through a vapor line 54 and passed through condensers 56 in which the propane is condensed under a suitably high pressure, and from which the condensate is conducted through a line 58 into a receiver 60. This receiver is provided with an automatic pressure relief line 62 and with a float valve controlled line 64 through which the liquid propane is conducted into a propane storage tank 66. The outlet temperature from the pressure still 12 may be controlled by conducting liquid propane from receiver 60 through a line 68 into the upper part of the still 12 onto one of the upper trays therein.

15 The petroleum oil recovered in the process, and which is of particular value for lubricating purposes, is discharged at a reduced pressure from the lower part of pressure still 12 through a liquid level valve controlled line 70 into a steam stripping contact chamber 72, in which the last traces of propane are removed. The asphalt- and propane-free oil is conducted from stripper 72 through a liquid level valve controlled line 74 and passed to storage through heat exchanger 52 where the heat contained in the oil is used to preheat the oil being introduced into still 12. The propane vapors and steam separated in stripper 72 are conducted through a vapor line 76 and a condenser 78 into a water separator 80. The propane remains uncondensed in the condenser 78 and is conducted from separator 80 through a line 82, placed under pressure by means of a compressor 84 and forced through a line 86 into the upper part of pressure still 12, where the propane is mixed with the vapors produced directly from the oil. It will be understood that a superatmospheric pressure up to 400 pounds or more per square inch is maintained in the still 12, condensers 56 and receiver 60, according to the hydrocarbon used as diluent, while a relatively low pressure of slightly more than atmospheric may be maintained in the stripper 72.

35 As soon as settling chamber 34 is filled sufficiently with settled asphalt, the stream of oil-asphalt-diluent mixture flowing through lines 28 and 30 is turned into chamber 36 by opening the valve in branch pipe 40, and closing the valve in branch line 32. The oil blend thereupon continues to flow into settling chamber 36 until it is sufficiently filled with asphalt after which the valve in branch line 42 is opened and the valve in branch line 40 is closed. From the chamber 36 the asphalt-free oil blend is conducted through the overflow line 44 and a valved connecting line 47 into the line 46. When the chamber 38 is cut into the system, the asphalt-free oil blend passes through the overflow line 44 and a valved connecting line 49 into the line 46. When the asphalt-free oil is being conducted through the line 47 the valves in lines 46 and 49 are closed.

55 Assuming that the stream of oil blend from the mixer 26 is being conducted into chamber 36 after completing the chamber 34, it will be apparent that the body of asphalt in the latter chamber will contain a substantial amount of occluded oil. This oil is washed from the asphalt with fresh liquid propane. Liquid propane to be used in the process is therefore withdrawn from storage 66 and conducted through a line 88, in which is mounted a pump 90 and a flow control valve 92, and passed into a distributing line 94. This line 94 is provided with valved branch lines 96, 98 and 100 which connect respectively into settling chambers 34, 36 and 38 through branch lines 32, 40, and 42. The liquid propane is con-

ducted from the line 94 through the branch lines 96 and 32 into the chamber 34, and distributed into the body of asphalt therein, for the purpose of washing the oil therefrom. The wash liquor overflows from the chamber 34 through the discharge line 44, a valved branch line 102 and a line 104, into the line 24, where the propane wash is mixed with the oil stock to be deasphalted. The quantity of oil washed from the asphalt in chamber 34 or any of the other chambers 36 and 38, is not sufficient to materially affect the propane as a blending agent in chamber 26. In fact, the quantity of propane, sufficient for later use in the process, would be so great compared to the oil removed from the asphalt body, that the oil would have no appreciable affect on the blend formed in mixer 26. This operation however is very effective for removing the oil from the asphalt in chamber 34. The chambers 34, 36 and 38 are cut into the system successively as asphalt precipitation chambers, and then cut into the leaching system for removing the oil from the precipitated asphalt. Chamber 36 is connected with the line 94 by means of valved line 98 for the admission of 25 liquid propane, and the extract is removed therefrom through overflow line 44 and a valved connecting line 106 which connects into line 104. Similarly in the leaching of asphalt in chamber 38, the liquid propane is admitted through valved 30 line 100 and the wash liquor discharged through overflow 44 and a valved branch line 108 which connects with the line 104.

In the continuous operation of the system, the proportion of liquid hydrocarbon conducted 35 through the lines 88 and 104 to be mixed with the oil flowing through the line 20 may be automatically regulated by means of an automatic proportioning regulator 110 which is connected into the flow meter or measuring device 22 and automatic valve 92. The regulator may be set to properly proportion the amounts passed through lines 20 and 88.

The body of asphalt collected in the chamber 34 following the washing with liquid propane 45 contains some propane and a small amount of oil. The propane is removed from the asphalt by closing the valves in lines 96 and 102 (the valves in lines 32 and 46 are closed), and opening the valves in the vapor discharge line 112 which discharges into a main vapor line 114 leading to a tower 116. The asphalt mixture is then heated under a superatmospheric pressure to a temperature sufficient to vaporize all of the propane and low 50 boiling oil constituents which may be present. These vapors are conducted into the tower 116 in which the propane is separated as a vapor and conducted through a vapor line 118, condensers 120, and into a receiver 122. The oil condensed 60 in tower 116 may be withdrawn to storage through a valved discharge line 124. The chamber 122 is provided with a float valve controlled discharge line 126 (part not shown) for conducting liquid propane to storage 66 and with a vapor line 128 65 which may connect into compressor 84. An automatic pressure relief line 130 also connects into the chamber 122 through the line 128. The outlet temperature in tower 116 may be controlled by passing regulated amounts of liquid propane from 70 receiver 122 through the return line 132.

The asphalt mixture in chamber 34 is heated by means of an indirect heating medium passed through a heating coil 134 mounted therein. This coil is supplied with a fluid heating medium such 75

as a high boiling point oil or other suitable fluid which is circulated through a heating coil 136 of a pipe still heater 138. The heating medium is passed through the coil 136 by means of a pump 140 and a valved connecting pipe 142, and discharged from the heater through valved pipes 144, 146, 148, a pipe 150, and a valved connecting pipe 152, which connects with the inlet of the coil 134 in chamber 34. The oil is circulated continuously through the coil and heater until the necessary heating is completed. The oil from the coil 134 passes through a valved connecting pipe 154 and through a pipe 156 to the pump 140.

Each of the chambers 36 and 38 is provided with vapor outlets 113 and 115 which connect with vapor line 114, and is also provided with coils 134 and connected into the heating coil 136 by suitable pipe connections. The coil 134 in chamber 36 is provided with a valved inlet pipe 157 which connects into the pipe 150, and with valved outlet pipe 158 which connects into the inlet of the pump 140. The coil 134 in chamber 38 is provided with a valved inlet pipe 160 which connects into the pipe 150, and with a valved outlet pipe 162 which connects into the pump inlet pipe 156. By suitably setting the valves in the various pipes referred to, any one of the chambers may be connected into the heating system.

After the asphalt in chamber 34 has been heated for a sufficient time to remove substantially all the propane and oil, the asphalt may be stripped with steam, introduced through a perforated distributor pipe 164. Each of the chambers 36 and 38 is also provided with a similar distributor pipe. Following this stripping, the asphalt in chamber 34 may be withdrawn while hot through a valved discharge line 166, or the asphalt may be first blown with air admitted through the valved line 164 for the purpose of producing a road asphalt, and then discharged through the line 166. In the blowing operation, the vapors and air may be conducted through the lines 112 and 114 into the tower 116 and the air or gases vented from receiver 122. In this operation of course, it will be understood that receiver 122 will not be connected into the propane storage 66 or with the compressor 84. Instead of conducting the air and vapor constituents into the tower 116 they may be bypassed from the line 114 into other suitable condensing or treating means.

During the blowing operation in chamber 34 considerable heat may be developed, but the temperature of the asphalt may be controlled by circulating a cooling medium through the coil 134. This may be accomplished by using the same fluid which is used for heating, cutting out the heating coil 136 by closing the valves in lines 142 and 144, and passing the fluid from the pump 140 through line 146 and a valved branch line 168, into a cooler 170. The cool fluid is discharged from cooler 170 through a valved branch line 172 and into the lines 150 and 152. In this operation it will be understood that the valve in line 148 will be closed, and that the valves in lines 152 and 154 are open, so that the fluid may be circulated continuously through the cooler 170 and the coil 134.

As the chambers 36 and 38 are cut into the system for removing the hydrocarbon from the asphalt, the cooler 170 may be cut into the system at the proper time in the manner referred to above in connection with chamber 34.

While the process of the present invention has been described in connection with the use of

liquid propane as a precipitating or diluting medium, it is to be understood that the invention is not limited to this particular hydrocarbon, but that low molecular weight hydrocarbons such as methane, ethane, propane, the butanes, the pentanes, the corresponding olefins and naphthenes and mixtures thereof may be used. Furthermore, a mixture of any of these constituents with other hydrocarbons, may be used as a diluent provided the specific gravity of the diluent is not higher than that of pentane. The diluent may be blended with the asphalt-containing oil in any suitable manner, for example, the diluent may be absorbed into the oil under pressure while cooling the absorption mixture. Where a mixture of hydrocarbons is used as the diluent, a mixture of relatively narrow boiling range is preferred because of the greater ease in controlling the temperatures and pressures which are necessary in carrying out the process. Such a mixture may comprise one of the commercial products now produced by the fractionation of natural gas or cracking still gases.

The process of the present invention may be varied in many respects without departing from the spirit and scope thereof, and the apparatus may be altered to suit the particular conditions which may be encountered in the treatment of any particular asphalt-bearing stock. The oil produced by the process, if removed from the asphalt at a comparatively high temperature, may contain some wax or petrolatum which may not precipitate. This may be removed in a subsequent operation at a lower temperature so as to completely prepare the oil for lubricating purposes. In the foregoing description three asphalt separating chambers have been described but any number may be used in the system according to the specific cyclic operation to be carried out. Instead of settling the asphalt from the oil by gravity, it may be removed by filtration or by centrifugal separation.

Having thus described the invention in its preferred form, what is claimed as new is:

1. The process of separating asphalt from asphalt-bearing oils, which comprises continuously mixing a stream of oil to be treated with a substantial proportion of a low gravity blending agent comprising a hydrocarbon diluent selected from the group of hydrocarbons consisting of methane, ethane, propane, the butanes, the pentanes, the corresponding olefins and naphthenes, and mixtures thereof, passing a stream of the resulting mixture into one of a plurality of enlarged settling zones in which the asphalt contained in the oil is precipitated therein until a substantial quantity of asphalt is contained in said zone, thereafter diverting said stream of oil mixture from said enlarged zone into another zone of said plurality of enlarged zones to deposit asphalt therein, introducing fresh blending agent into the precipitated asphalt contained in said first-mentioned zone following said precipitation to wash any occluded oil therefrom, removing the washed asphalt from the enlarged zone, utilizing the wash liquor from said washing operation for blending with said fresh asphalt bearing oil introduced into the process to supply at least in part the blending agent, and continuing the operation by using the plurality of enlarged zones separately and successively as asphalt-precipitation zones.

2. The process defined by claim 1 in which the asphalt mixture contained in each settling zone is cooled during the precipitation of asphalt and

the washing of the precipitated asphalt therein, and thereafter heating the asphalt mixture in each settling zone following the washing of the oil therefrom to vaporize and thereby remove the blending agent from the precipitated and washed asphalt.

3. The method of separating asphalt from a hot asphalt-containing residuum produced in a distilling operation, which comprises passing the hot residuum in indirect heat exchange with an oil mixture being distilled in a distilling zone to heat the oil mixture and effect distillation of a portion thereof, thereafter mixing a low gravity blending agent with said residuum to substantially dilute said residuum and precipitate the asphalt contained therein, said agent comprising a hydrocarbon or mixture of hydrocarbons selected from the group consisting of methane, ethane, propane, the butanes, the pentanes, the corresponding olefins and naphthenes, passing the mixture of residuum and blending agent alternatively into the respective chambers of a plurality of asphalt settling chambers and therein permitting the settling of the asphalt from the diluted oil mixture, decanting separated oil

and blending agent from the mixture in each settling chamber during the time the mixture is supplied thereto and conducting it into said distilling zone wherein the blending agent is vaporized and distilled from the oil thereby recovering an asphalt-free oil as a product of said asphalt-containing residuum.

4. An apparatus for removing asphalt from asphalt-containing oils, comprising means for mixing asphalt-containing oil with a low gravity blending agent, a plurality of asphalt settling chambers, and means for separately conducting the asphalt oil-blending agent mixture into any one of said chambers, means for separately introducing blending agent into each of said chambers to wash the asphalt deposited therein while asphalt is being precipitated in another chamber, and means for conducting the wash liquor from each of said chambers to the means for mixing the blending agent with asphalt-containing oil.

5. The apparatus defined by claim 4 in which means is provided for heating and for cooling the contents of said settling chambers.

DAVID G. BRANDT. 25
